CLAIM

The ornamental design for the rack and shelf system to hold clear acrylic bulk food containers, as shown and described.

DESCRIPTION

FIG. 1 is a top plan view of a rack and shelf system to hold clear acrylic bulk food containers showing my new design;

FIG. 2 is a left side elevational view thereof;

FIG. 3 is a rear elevational view thereof;

FIG. 4 is a bottom plan view thereof;

FIG. 5 is a right side elevational view thereof;

FIG. 6 is a front elevational view thereof; and,

FIG. 7 is a perspective plan view thereof.
